PLATE OR SIMILAR ARTICLE

Takeshi Inoue, Atsuta-ku, Nagoya, Japan, assignor to Noritake Co., Inc., New York, N. Y., a corporation of
New York

Application November 29, 1954, Serial No. 33,280

Term of patent 7 years

(Cl. D44—15)

Fig. 1

Fig. 2

Fig. 1 is a plan view of a plate or similar article, showing my new design.

Fig. 2 is a fragmentary plan view, to enlarged scale, showing the central design of the plate shown in Fig. 1.

The plate is of a conventional configuration when viewed from the side and bottom thereof.

I claim:

The ornamental design for a plate or similar article, substantially as shown and described.
